CARTON FOR FRAGILE ARTICLES

Samuel Bergstein, Cincinnati, Ohio

Application October 3, 1932, Serial No. 635,970

5 Claims. (Cl. 229—29)

My invention relates to the type of cartons used for the packaging of eggs and Christmas tree ornaments and the like, that require cushioning from contact with each other to prevent 5 breakage.

It is an object of my invention to provide an improved carton having a series of pockets with lateral partitions formed and cut in a carton blank, together with a longitudinal insert partition which subdivides the pockets and thereby prevents contact between the articles packed in said carton.

Another object of my invention is to provide a carton for fragile articles, the bottom of which is supported on legs composed of two ply layers of board which are folded and sealed together continuously during the making of the carton and which prevent the bottom of the box from contacting surfaces upon which the box is set, thereby preventing the breakage of articles contained within the carton. Another object is the provision of a carton having pockets formed by partitions formed integrally with the side walls, which partitions may be bent out at right angles 20 to the side walls and held in rigid position in slots in the bottom walls, with scored attachment portions extending in different planes between the side walls and the partitions, thereby reinforcing the connections between the side walls 25 and the partitions.

A further object of my invention is to provide a carton having an elevated bottom supported on legs rendering the bottom resilient to shocks, thereby preventing the breakage of fragile articles 30 contained therein.

A further object of my invention is to provide a partitioned carton in which the ends of a centrally positioned longitudinal partition having depending tongues that protrude through slots in 40 the bottom of the box, and which interlock in the slots in the bottom, thereby holding a series of vertical partitions in position, increase the rigidity of the box and form an additional protection for the box bottom. It is further my object to provide a carton in which the partition tongues are wedged in position in the bottom wall of the carton, thereby increasing the rigidity 45 of the box and preventing removal of the central partition.

These and other objects will be more specifically pointed out in the specifications and the drawings forming part of this application.

In the drawings:—

Figure 1 is a plan of the carton blank showing 55 the cuts and scores.

Fig. 2 is a plan of the central partition or comb.

Fig. 3 is a perspective of the blank showing a fold that forms one of the legs of the carton.

Fig. 4 is a perspective of a carton in the knock down condition.

Fig. 5 is a perspective of a carton with the lateral partitions in place and ready to receive a central partition or comb.

Fig. 6 is a perspective of a carton showing a comb in place.

Fig. 7 is a perspective of a completed carton with its lid closed.

Fig. 8 is a fragmentary section taken on the line 8—8 of Fig. 6.

Fig. 9 is a section taken on the line 9—9 of 15 Fig. 8.

The blank 1 has a pasting flap 2 depending from a cut and scored section 3. The section 3 comprises a series of lateral partitions 4. In the tops of these partitions there are slots 5 for receiving a longitudinal partition or comb to be later described. The bottom edges 6 of the partitions have arched cut out sections 7 and beveled edges 8 so as to form rectangular tabs 9, which fit into elongated slots 10 in a bottom 11 of the carton. 20 The partitions are bent along scores 12 and when they are bent downward leave trapezoidal-like sections 13 which strengthen the carton against collapse when it is set up.

The sides 14 and 14a of the carton are defined 30 by the scores 15, 15a, 15b and 15c and the scores 16 and 16a together with the scores 15a and 15b define the leg sections of the cartons. The scores 16 and 16a are cut through in a series of places in order to facilitate the setting up of the carton. 35

The bottom of the box has the elongated slots 10 and other elongated slots 18 perpendicular to the slots 17. The slots 18 are cut practically all around except for a section 19. This section provides a hinge or supporting area for latch pieces 40 20. The front edges 21 of these latch pieces press against the necks of the comb tabs and prevent the withdrawal of the comb, also increasing the rigidity of the box.

The cover section is shown between the scores 45 15c and 22a, from which extends the cover locking piece 23. The locks are formed by slots 24, into which the trapezoidal sections fit. Tongue sections 24a extend approximately half way across the slots and these tongues hook on the underside of the trapezoidal sections and keep the cover closed.

The comb or central partition 25 has slots 26 which intermesh with the slots 5 of the lateral partitions to strengthen them at their tops. Be- 55

tween the slots there are tapered sections 27, the upper ends of which terminate in a mushroom like portion 28, the necks 29 being considerably smaller than the heads 30 and thereby providing a ledge-like edge 31 which hooks into the slots 18. At the sides 32 and 32a there are legs 33 and 33a. The depth of the comb is such that its upper end 34 will extend considerably above the top edges 35 of the lateral partitions so as to prevent the cover from contacting articles contained within the carton.

Adhesive is applied to the sections 36, 37 and 38. The blank is then double folded to form one of the legs 38, as can be seen by reference to Fig. 3. The blank is then folded over along the score 15, and the section 36 is pasted to the side 14. Simultaneously with the pasting of the section 36, the pasting flap is also pasted to the side 14a with the edge 39 in line with the score 15c. The section 36 forms the other leg 40. After pasting the carton will appear in knock down condition, such as is shown in Fig. 4.

Fig. 5 shows how the carton is then set up with the lateral partitions placed in a vertical position with their tabs extending through the slots 10. The comb or central partition is then put in place by pushing the heads 30 through the slots 18, until the edges 31 hook on the under side of the bottom. The slots of the comb will then be interlocked in the slots in the lateral partitions and prevent them from bending out of shape or place.

As illustrated, the carton, when completely assembled, will have side legs extending across its length, and also a series of disconnected legs formed by the sections 30 of the comb. This construction provides a raised bottom on the carton and insures edge and point contact of the bottom of the carton with any surface that the carton may be placed upon.

Having thus described my invention, what I claim as new and desire to secure by Letters Patent is:—

1. A carton formed from a cut and scored blank having a raised slotted bottom with portions contiguous with side edges of said bottom folded and secured together forming two ply ribbed supports integral with side walls of said carton, and partition flaps integrally secured to said side walls having tongues extending through the slots in said bottom and forming additional bottom supports for said carton.

2. A carton formed from a cut and scored

blank having a raised slotted bottom with portions contiguous with side edges of said bottom folded and secured together forming two ply ribbed supports integral with side walls of said carton and partition flaps integrally secured to said side walls having tongues extending through the slots in said bottom and forming additional bottom supports for said carton, and a longitudinal partition forming member interlocking said partitions, said longitudinal member also having tongues extending through slots in said bottom member.

3. A carton formed from a blank and comprising side walls with their lower extremities folded in double folds forming supporting ribs, said folds being rigidly secured together, transverse partitions dependent from said side walls having locking tabs, a bottom extending between the upper edges of said doubly folded portions, slots in said bottom to receive said tabs on said lateral partitions and to hold them in place, and a longitudinal partition having extensions engaging under the bottom, providing means for securing said longitudinal partition against upward movement from said bottom, said extensions of said longitudinal partitions providing middle supports for said bottom, additional to said supporting ribs, preventing said bottom from making full surface contact.

4. A carton comprising a sheet folded to form a bottom and side walls, the bottom having a series of slots each formed by partially severing a portion thereof, leaving a junction of said portion on which said portion may bend down to leave the slot, cross partitions in the carton, and a longitudinal partition interlocking with the cross partitions and bearing down thereon and having on its lower edge a series of hooking tabs snapped through the respective bottom slots to hook under the carton bottom, and being gripped by the bent down portions of the bottom.

5. A carton as set forth in claim 4, in which the junction portions of the bottom and side walls are folded to form depending reinforcing and supporting ribs for the carton, each made up of two plies of the sheet, said plies being rigidly secured together, and said ribs and the hooking tabs of the longitudinal partition collectively constituting means for supporting the bottom of the carton in raised position for effective cushioning support of articles in the cells formed by the series of cross and longitudinal partitions.

SAMUEL BERGSTEIN.
